UNITED STATES PATENT OFFICE.

WILLIAM A. JAMESON, OF NIAGARA FALLS, NEW YORK.

DESIGN FOR A HANDLE FOR SPOONS, FORKS, OR SIMILAR ARTICLES.

SPECIFICATION forming part of Design No. 34,055, dated February 12, 1901.

Application filed January 21, 1901. Serial No. 44,230. Term of patent 7 years.

To all whom it may concern:

Be it known that I, WILLIAM A. JAMESON, a citizen of the United States, residing at Niagara Falls, in the county of Niagara and State of New York, have invented and produced a new and original Design for a Handle for Spoons, Forks, or Similar Articles; and I do declare the following to be a full, clear, and exact description of the same, reference being had to the accompanying drawings, forming a part thereof.

The leading features of my design consist in the peculiar outline of the handle and the ornamentation of the obverse and reverse sides thereof.

Figure 1 is a view of the obverse side of a spoon, showing my handle attached to the bowl thereof; and Fig. 2, a reverse side of the same.

In the drawings the letter *a* indicates the bowl of a spoon or the tines of a fork, the latter being shown by dotted lines, to which the handle *b* is attached. For a short distance from the junction of the handle with the bowl the marginal edges of the handle are approximately parallel to about midway its length or to the point *c*, from which point they curve slightly outward, ending abruptly at the point *d*. From this point the edges swell slightly outward and then with a gradual inward curve disappear at the point *e*. Slightly below the point *e* the edges assume an abrupt outward and inward curve to the point *f*, and from this point they have a slight inward curve and then a gradual outward curve to the corners of the top of the handle, which are slightly round. The top outline of the handle is approximately a gradual downward incline in opposite directions from the center to the corners.

The ornamentation of the obverse side consists of a narrow central panel running the entire length of the shank of the handle, at the lower end of which appears scroll-like ornaments. Upon each side of this panel are 45 elongated marginal ornaments intersected by a series of knobs or bead-like projections. The upper portion of the handle is ornamented by an oval-shape panel or shield inclosed on its sides by marginal threads and 50 surmounted by foliated scrolls around a small central oval shield or panel.

The ornamentation of the reverse side consists of marginal lines or threads extending from the lower part of the handle to a little 55 over half of its length, said marginal lines or threads being intersected by knob or bead like ornaments, the marginal lines or threads having their lower ends disappearing between the upper ends of the intersected beads and 60 their upper ends disappearing in foliated scrolls at the upper portion of the handle, these marginal lines or threads and other ornamentations forming a long narrow panel running the entire length of the shank of the 65 handle and a widened panel or shield at the upper portion of the handle.

Having thus fully described my invention, what I claim as new, and desire to secure by Letters Patent, is—

The design for the handle of a spoon, fork, or similar article, as shown and described.

In testimony whereof I have signed my name to this specification in the presence of two subscribing witnesses.

WILLIAM A. JAMESON.
